(57) **CLAIM**

The ornamental design for a tow hitch protector, as shown and described.

DESCRIPTION

FIG. 1 is a perspective view of an embodiment of the tow hitch protector showing my new design.

FIG. 2 is a front elevation view thereof.

FIG. 3 is a rear elevation view thereof.

FIG. 4 top plan view thereof.

FIG. 5 is a bottom plan view thereof.

FIG. 6 is a right side elevation view thereof; and,

FIG. 7 is a left side elevation view thereof.

The broken lines shown in the figures depict portions of the article that form no part of the claimed design.
